UNITED STATES PATENT OFFICE.

ALBERT EDWARD BROWN, OF TEESWATER, ONTARIO, CANADA.

DISPLAY-STAND.

No. 869,053.

Specification of Letters Patent.

Patented Oct. 22, 1907.

Application filed May 16, 1907. Serial No. 373,906.

To all whom it may concern:

Be it known that I, ALBERT EDWARD BROWN, a citizen of the United States, and a resident of Teeswater, Ontario, Dominion of Canada, have invented a new 5 and Improved Display-Stand, of which the following is a full, clear, and exact description.

The invention relates to store furniture, and its object is to provide a new and improved portable display stand, more especially designed for displaying wall coverings and accessories in stores or by canvassers, and in such a manner that the customer receives the impression of the entire wall covering for a room, such as the main covering, the border, ceiling, moldings, plate rails, etc., the arrangement being such to permit the dealer to 10 quickly change the sample wall coverings and to permit of conveniently placing sample wall coverings in position on the stand or removing the coverings therefrom.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

25 Figure 1 is a side elevation of the improvement; Fig. 2 is a front elevation of the same; Fig. 3 is a perspective view of the improvement showing the sample wall covering displayed; Fig. 4 is a face view of one of the sample wall coverings and the supporting rods for the same; Fig. 5 is an enlarged transverse section of the improvement on the line 5—5 of Fig. 2; Fig. 6 is an enlarged rear view of one end of the molding, and means for attaching it to the sample wall covering; Fig. 7 is a sectional plan view of the same on the line 7—7 of Fig. 6; Fig. 8 is an 30 enlarged side elevation of the means for removably holding the moldings in place on the stand; Fig. 9 is a side elevation of the improvement in a folded condition; Fig. 10 is a side elevation of the upper portion of the stand, part being in section, Fig. 11 is an enlarged 35 sectional front elevation of the bearing for adjustably holding the supporting rod in place, and Fig. 12 is an enlarged side elevation of the fastening device for holding the display stand in a folded position.

The stand proper consists essentially of a top A and 40 front and rear legs B and C connected by hinges D and D' through the front and rear ends of the top A. The adjacent edges of the top A and the legs B and C are beveled, so that when the stand is set up, as illustrated in Figs. 1, 3 and 5, then the beveled edges fit 45 one on the other, to produce a firm joint between the top and the legs B and C. In order to hold the legs B and C from spreading apart a strap E is provided secured at E' to one side of the front leg B and adapted to engage a button E² held on the corresponding side of

the rear leg C. In practice, I prefer to make the front 55 leg B somewhat shorter than the rear leg C, so that when the stand is set up, as illustrated in Figs. 1, 2 and 3, then the top A is slightly inclined downwardly and forwardly.

On the top A of the stand are secured the rearwardly 60 extending curved bars F for removably supporting the sample wall coverings G, each supporting bar F having its ends terminating in eyes F' (see Figs. 5 and 10) fitting against the under side of the top A and secured thereto by screws F².

65 The sample wall coverings G are each formed of a main body portion G' and an extension G², which may be the upper third of a wall and may terminate in a border or ceiling G³, to allow of displaying the entire wall covering for a room, including the wall, border 70 and ceiling to be covered by wall paper, as well as a molding H, or a plate rail I, supporting plates J and located at the junction of the main portion G' and the extension G², the plate rail I having hooks I' adapted to be hung on the supporting bars F at the front ends 75 thereof.

Each molding H is provided at its ends with spring 80 clasps H' (see Figs. 3, 6 and 7) for engaging the sides of the extension G² of a sample, to hold the molding H in the proper position on the extension.

Each of the sample wall coverings G is preferably provided at the junction of the main portion with the extension G² with loops G⁴ and cut-out portions G⁵, for the passage of the supporting bars F (see Fig. 4), the said loops G⁴ receiving pins G⁶ extending across 85 the cut-out portions G⁵ and engaging the rear sides of the supporting bars F, so as to hingeably connect the sample G with the supporting bars F, it being understood that on the withdrawal of the pins G⁶, a sample can be readily removed from the supporting bars F. 90

Now when a sample is to be displayed on the stand, the body portion G' is swung down onto the front leg B while the extension G² is swung upward to form a continuation of the main portion G', as plainly indicated in Fig. 3. The upper end of the extension G² 95 is engaged by a spring clasp K held on the angular arm L' of a rod L, mounted to slide up and down in a bearing N secured to the right hand side of the leg B near the upper end thereof, the rod L being fastened in place after the desired adjustment has been made 100 by a set screw N' (see Figs. 2, 3 and 11). Now by the arrangement described the entire sample as well as the molding H and the plate rail I can be displayed to the greatest advantage, so that the customer receives the impression of the entire wall covering for a room. 105

The different shaped moldings H are normally supported on the top A and extend through loops O made of leather or other suitable material, and secured to

the upper side of the top A. The ends of the moldings H are engaged by buttons P secured to the sides of the top A, so as to hold the said moldings H against movement while in position on the top A and held in the 5 loops O.

The rear leg C is provided with a suitable strap Q, to permit of conveniently carrying the stand about when used by a canvasser, it being understood that the stand is capable of being folded into comparatively 10 small space and with the sample G between the front and rear legs B and C, as plainly illustrated in Fig. 9. For this purpose the legs B and C are swung over so as to place the top A upside down, whereby the supporting bars F extend on the under side of the top and consequently support the downwardly hanging samples 15 G between the legs B and C.

The strap E is disconnected from the button E² previous to folding the stand and then the rod L is slid down the bearing N until the angular arm L' rests 20 on top of the bearing N. The strap E is now passed around the rear leg C and is fastened onto a staple L² after which the end of the supporting rod L is passed through the staple L² to lock the end of the strap E in place, thus holding the several parts in a locked position. The rod L after engaging the staple L² is fastened 25 in place by the set screw N'. By folding the stand as described, the strap Q is brought to the outside, so as to be conveniently engaged by the arm of the canvasser, to enable the latter to carry the stand 30 about and with it the sample held thereon.

Having thus described my invention, I claim as new and desire to secure by Letters Patent:

1. A display stand comprising a top, front and rear legs hingedly connected with the said top at the front and rear 35 edges thereof, the top and the upper ends of the front and rear legs being beveled, supporting means for the material to be displayed carried by the top of the stand, the said legs being adapted to be swung over to place the top upside down with the displayed material extending between 40 the legs, and means for securing the parts of the stand in folded position.

2. A display stand comprising a top, front and rear legs hinged to the top at the front and rear edges thereof, the top and the upper ends of the front and rear legs being beveled, 45 means for holding the front and rear legs against spreading, supporting bars secured to the top for supporting the material to be displayed, and vertically adjustable supporting means carried by the said stand.

3. A display stand comprising a top, front and rear legs 50 hinged to the top at the front and rear edges thereof, the top and the upper ends of the front and rear legs being beveled, the front leg being shorter than the rear leg to cause the top to incline downwardly and forwardly when the stand is set up, means for holding the front and rear legs against 55 spreading, and supporting bars extending across the top and secured at their ends to said top for supporting the material to be displayed.

4. A display stand comprising a stand proper, means on 50 the top of the stand for holding a sample wall covering having an extension, and an adjustable support on the said stand and adapted to engage the said extension to dis-

play the latter upwardly as a continuation of the sample wall covering.

5. A display stand comprising a stand proper, sample wall coverings each having an extension, means on the 65 stand for holding the sample wall coverings, and a support for holding the extension as a continuation of the sample wall covering.

6. A display stand comprising a stand proper, sample wall coverings each having an extension, means on the 70 stand for holding the sample wall coverings, a support for holding the extension as a continuation of the sample wall covering, and a molding having attaching means for securing the molding to the extension.

7. A display stand comprising a stand proper, sample 75 wall coverings each having an extension, means on the stand for holding the sample wall coverings, a support for holding the extension as a continuation of the sample wall covering, and a rail for removable attachment to the said stand at the junction of the sample wall covering and 80 its extension.

8. A display stand comprising a stand proper, a sample wall covering having a body portion, and an extension of the same, the said body portion having loops and cut out 85 portions, pins extending through the said loops and across the cut out portions, and curved supporting bars on the top of the stand and engaging the pins at the cut out portions.

9. A display stand having a top provided with transverse loops for the reception of moldings, and buttons at the 90 sides of the top for engaging the ends of the moldings to hold the same in position on the said top and in the said loops.

10. A display stand comprising a top, front and rear legs hinged to the said top, curved supporting bars extending across the top and secured at their ends to the top, the 95 said supporting bars being adapted to hingedly support the sample wall coverings to be displayed, a bearing on one side of the front leg, a supporting rod adjustably secured in the said bearing and having an angular arm at its upper end, and a clasp on the said angular arm for engaging the 100 upper edge of the sample wall covering.

11. A folding display stand comprising a top, front and rear legs hinged to the said top, supporting means carried by the top of the stand and adapted to support a sample wall covering, the said legs being adapted to be swung over 105 to place the top upside down with the sample wall covering extending between the legs, and a strap secured at one end to one side of the front leg and adapted to be passed around the rear leg, when the parts are in folded position, and secured at its other end to the opposite side of the 110 front leg.

12. A folding display stand comprising a top, front and rear legs hinged to the said top, supporting means carried by the top and adapted to support a sample wall covering, the said legs being adapted to be swung over to place the 115 top upside down with the sample wall covering extending between the legs, a strap secured at one end to one side of the front leg, a staple on the opposite side of said leg, the said strap being adapted to be passed around the rear leg, when the parts are in folded position and secured to the 120 said staple, a bearing on the side of the front leg, a rod adjustable in said bearing and adapted to pass through the said staple to lock the end of the strap in place, and means for fastening the rod in position.

In testimony whereof I have signed my name to this 125 specification in the presence of two subscribing witnesses.

ALBERT EDWARD BROWN.
